UNITED STATES PATENT OFFICE

VINCENT RUIZ, OF NEW YORK, N. Y., ASSIGNOR TO JACOB THOMAS BASSECHES, OF NEW YORK, N. Y.

FOLDING CHAIR

Application filed November 28, 1928. Serial No. 322,303.

This invention relates to folding chairs, more particularly to folding arm chairs.

My invention has for an object thereof the provision of a folding chair now popularly used in the home for such purposes as card games and the like and more particularly resides in providing a folding chair which has combined therewith arm rests. It is contemplated by my invention to provide a new and novel folding chair having arm rests, the elements forming the chair and arms giving the comfort of an arm chair and the compactness of a folding chair.

It is still further an object of my invention to provide a folding chair which has rigidity of construction and extreme comfort in use characterized by features of roominess and arm resting portions, without sacrifice of compactness in storage characterized by the rigid elements and arms being foldable in a layer corresponding to no greater thickness than that of the material of which the main element of the chair is composed. It is contemplated by my invention to provide a combined folding chair and arm rests which is susceptible of extreme ornamentation, as when made of bent wood forming the main frame and including a seat and arm rests capable of being foldable into no greater thickness than the frame whereby the maximum size seat will still be obtained and the comfort of rests for the arms as in larger and completely rigid arm chairs.

It is still further an object of my invention to provide a folding chair, including arm rests which are equally foldable into alignment with the main frame of the chair, characterized by all the elements forming the chair, such as seat, supports or legs, frame and arms being coordinated to set up the chair in usable position of its seat and arm rests at a single operation or collapsed into a compact form for storage or for similar purposes.

Other objects of my invention reside in the provision of a folding chair including arm rests which are foldable so that the entire chair may be folded compactly or set up quickly at will, the invention further contemplating foldable arm rests and mounting means therefor to simply and quickly

move from a folded position in alignment generally with that of the frame to one where in use they will comfortably and rigidly sustain the weight of the arms or elbows of the user. It is still further contemplated by my invention to include in a folding chair, foldable arm rests whereby the latter may be moved to a usable position and give maximum rigidity for its intended function in supporting the arms of a person, or retracted to the folded position in alignment generally with the frame of the chair without interfering with such elements as the seat and the legs whereby the maximum seating capacity will be retained for use without sacrifice of compactness when not in use.

Other objects of my invention reside in the provision of a folding chair including arm rests which are equally foldable, of simple design and rigid construction to give co-ordinating folding action, with the folding elements of the chair and elements thereof.

To attain these objects and such further objects as may appear herein or be herein-after pointed out, I make reference to the accompanying drawings forming part hereof, in which—

Figure 1 is a side elevation, sectional view of my chair in the set up position;

Figure 2 is a similar view of my chair in the folded position;

Figure 3 is a front view of my device as set up;

Figure 4 is a fragmentary enlargement of a leg and frame joint when the chair is set up;

Figure 5 is a section taken on a line 5—5 of Figure 4;

Figure 6 is a view similar to Figure 5 with the chair in the folded position;

Figure 7 is a section taken on the line 7—7 of Figure 5;

Figure 8 is a section taken on the line 8—8 of Figure 6;

Figure 9 is a section taken on the line 9—9 of Figure 8;

Figure 10 is a section taken on the line 10—10 of Figure 1;

Fig. 11 is a perspective view showing the connection between the arm and rear leg.

Making reference to the drawings, my in-

vention may best be illustrated in connection with a folding chair 10, in which the main frame 11 comprises a U-shaped bent wood strip whose downwardly depending legs 12, 13 are braced and connected by the strut 14 located in the legs 12 and 13 approximately at the midpoint of the strip from either of the edges. The lower ends 12' and 13' are angularly cut so that they may lie level with the floor line. The thickness of the strip material will give substantial depth towards the rear of the strut 14 for purposes which will appear as this description proceeds. The upper end of the frame is preferably of slightly lesser depth than the thickness of the strip, at which point there is provided a back rest 15 of any suitable material, such as plywood. Substantially near the center of the frame 11, between the legs 12 and 13, I pivotally mount a seat member 16 and this may be made of suitable material such as plywood and upholstered material 17 to lend greater comfort and decorate the upper surface.

For pivotally mounting the seat so described, the legs 12 and 13 are provided with pivots 18. These may be a metal casting or forging suitably set in the body of the material forming the leg 12. The pivot so formed is preferably located so that its pivotal point is to one side of the center line of the strip forming the leg 12. To each side of the seat 16 I provide pivotal points 19, which are preferably formed upon the channel member 20, as by upsetting the same from a metal stamping of that form and the branches of this channel fixed in position on the seat by the rivet 21. In this manner, the seat may be positioned between the legs 12 and 13 and occupy substantially the full width between these members. Disposed upwardly between the legs 12 and 13 I provide the rear legs 22 and 23, connected to each other by the brace 24 and to the legs 12 and 13 adjacent its upper end 25 by the pins 26 as to permit pivotal movement of the legs. These pins are suitably headed to lock the legs securely in this pivotal position. These legs are preferably formed of a thickness less than the full width of the legs 12 and preferably arranged to lie flush with the legs 12 rearwardly of the brace 14. Intermediate the length of the legs 22 and 23, there is provided a slot 27 into which is arranged to be disposed the pintle 28 formed on the casting 29, attached to the rear portion of the seat 16 at 30, adjacent the offset portions 31, best shown in dotted line in Figure 3. It will be understood that the seat 16 is supported in the pivots 18 by the pins 19, projecting thereinto upon the frontal legs 12 and 13 and upon the legs 22 and 23 by the pins 28 extending in the slot 27. The upper wall 27' of the slot 27, forming a stop for the pin 28 to prevent upward pivotal movement of the

rearward portion of the seat 16, at the same time maintains the pairs of legs 12 and 13 and 22 and 23 not only in spaced relationship but also to serve as a means to move the legs to the open and closed position by mere pivotal swinging of the seat 16. It will further be observed that with the pivots 18 disposed to one side of the center line of the legs 12 and 13 and with the pin 28 offset as shown within the slot 27 in the folded position, as shown in Figure 2, the seat 16 and legs 22 and 23 may lie within the confines of the frame 22, without adding any additional thickness and when disposed in the folded position, as shown in Figure 2, the offset pin 28 will engage the slot 27 and prevent independent opening of the legs 22 and 23 from the folded position.

Upwardly disposed from the seat upon the legs 12 and 13, at a convenient position, I provide arm rests 32. These are arranged to be set up approximately at right angles to the legs 12 and 13, with the shoulders 33 abutting the frontal edge of the legs 12 and connected thereto for pivotal mounting inwardly of the body of the chair by the hinge assembly 34, having an arm engaging portion 35 preferably comprising a bent sheet metal strip to which the arm 32 is attached by rivets or other suitable connection. The arm engaging portion 35 is formed rearwardly thereof with a bearing portion 36 mounted within a U-shaped strap 37, through the spaced arms of which, 38 and 39, there is disposed the pintle 40, connecting this portion of the hinge through the bearing portion 36, previously described. The rearward wall of the strap 37 is connected to the L-shaped plate 41 by a rivet 42, loosely set so that it permits pivotal movement of the strap thereon. The hinged assembly thus described is all set within the cut out portion 43 within the frontal side of the legs 12 and 13 so as to dispose the arms 32 with their shoulders 33 abutting against the frontal portion of the legs 12 and 13, as more clearly shown in Figures 1, 4 and 5. The depending portion of the plate 41 is so disposed downwardly that the pin 26 passes therethrough, thereby forming reinforcing bearing portions for the pins 26 passing through the legs 12 and 13 at this point, as will be readily understood, when the main frame of the chair is made of wood. It will be observed that with the hinge mounting for the arms 32 as shown in the set up position, as shown in Figures 1, 3, 4 and 5, the arms 32 will be given all the rigidity necessary in performing their intended function as arm rests, preventing lateral and longitudinal displacement in their abutting position, as well as being prevented from outward displacement by the positive stopping action of the hinge itself and the limiting action of the abutment of the end 33 as above described. It will also

be observed that interior pivotal movement is not only upon the strap 37 on the axis of the pintle 40 but the strap itself, being mounted pivotally upon the pin 42, will give 5 double (vertical and lateral) movement to the hinge so that in its inwardly folded position, as more clearly shown in dotted lines in Figure 3, the arms 32 will be given an upward tilt, as more clearly shown by the position 10 of the arm engaging portion 35 in Figure 8. The advantages resulting from this combined pivotal and tiltable movement will appear more clearly as this description proceeds.

15 In order to coordinate the folding movement of the arms 32 with the setting up and folding of the chair, that is the legs 12 and 13, rear legs 22 and 23 and seat 16, it is preferred that the movement of these members relative- 20 ly to the general frame of the chair be such as to effect a simultaneous movement of the arm rests. For this purpose, the hinge assembly 34 has attached thereto at the cut out portions 43a of the arms disposed 25 interiorly thereof, an operating pin 44, riveted to the extension 35 so as to at the same time join these members by the connecting operation of upsetting the metal of the pin 44 to each side of the straps forming the mem- 30 ber 35. The pin 44 is suitably shaped at 45 to have a camming surface and is arranged to be disposed in engagement with the camming plate 46 attached adjacent the end 25 of the legs 22 and 23. The plate 46 is sub- 35 stantially L-shaped in cross section, with the interior facing 47 disposed on the end 25 of the leg adjacent the extension 41 and is similarly disposed so that it has an orifice through which the pin 26 passes, forming a 40 bearing surface therefor. This plate serves to reinforce the orifice of the legs 22 and 23 through which the pin 26 passes, particularly when the material of which the legs are made is wood. The plate 46 has a frontal branch 45 48, through which there may be passed a fastening element, such as a bolt 49. The plate 46 and the branch 48 thereby form a reinforcing corner for the end 25 of the leg and immediately thereunder the leg is cut 50 out at 50 so as to provide a clearance portion. The corner which forms part of the L-shaped plate 46 is cut away at 51 so as to have an enlarged clearance face 52, a laterally directed camming edge 53, a curvilinear edge 55 54, cooperating with the corner 55 to form a stop for the pin 44 when the arm is in the unfolded position, shown more clearly in Figures 4 and 5. The curvilinear edge 54 extends gradually into a camming edge 56 60 formed on the branch 48 of the plate. The combined curvilinear surfaces of the edge 54, forming the camming edge 56, is so formed in respect to the pivotal center running through the pin 26 that upon spreading of 65 the legs 12, 13 from the pair of legs 22 and 23, the upper end 25 of the rear legs will, through the medium of the camming plate 46 just described, engage the operating pin 44 to move the arms from the folded position to the collapsed position and vice versa. With 70 the arm as positioned in Figure 4 in the set up position, an upward tilting action of the seat 16 will serve to draw the rear legs 22 and 23 in alignment with the legs 12 and 13, actuating the same through the slot engagement of the extension 28 within this portion. Pivotal movement about the pin 26 will also angularly move the end 25 beyond the pin 26. During this movement the pin 44, particularly at its camming point 45, will be engaged by the camming plate 46 so as to have the camming edge 56 draw the pin inwardly and thereby pivot the arm about the pintle 40. The camming action of the camming surface 54 will not merely serve to draw the pin 44 to the folded position but by the combined action of the camming surface 56 and the radial displacement of the end 25 about the pin 26, will upwardly draw the pin 44 to simultaneously pivot the strap 37 about the pin 42, thereby causing a compound swinging and tilting of the arms 32. Downward tilting movement of the branch 35 and the arm carried thereby is prevented by extending the camming surface 56 at 57 to form a stop. Thus, when the pin is completely drawn to the folded position as more clearly shown in Figures 6 and 8, the downward tilting action of the branch 35 and the arm carried thereby will be sustained in this position by the stop 57, as just mentioned. By this compound movement, the upward curved edge 16' of the seat may be extended and the arms as folded will in no way serve to interfere with the making of the seat member of such size as to lend greater comfort to the user. 90

A clearance portion 43a on the arm will nest in the clearance portion 43b on the leg 22 to thereby permit more compact super-positioning of the edge of the leg and arm, and also give proper clearance between these parts.

To unfold the chair from the position just described, the upper edge 16' of the seat 16 is grasped in one hand and the back in the other, to separate the parts. The downward tilting action of the seat forces the legs 22 and 23 backwardly, the curvilinear movement of the pin 28 being compensated by movement within the slot 27. This action serves to pivot the legs 22 and 23 about the center 26, giving a proportionate movement to the end 25 extending beyond the pin 26. The outward corner 58 of the plate 46 combined with the camming action of the surface 56 serves to downwardly and outwardly move the arms 32 by actuating the pin 44 until at the fully distended position of the legs 22 and 23, the arms 32 are disposed with the shoulders 33 against the frontal portion of the legs 120 125 130

12 and 13 in butt-joint relationship. Continued outward folding is thereby prevented by this engagement, whereas the corner 55 serves to hold the pin 44 against inward tilting action.

In this way it will be observed that I have provided a folding chair or extreme compactness and simplicity of parts in that substantially only three main moving elements are 10 provided, including the actuation of the arm rests. It will further be observed that all the parts are coordinated so that a single movement of the seat in relation to the frame will set up the chair end arms into proper 15 position. Similarly, in folding the chair, a simple movement of the seat will serve to dispose the legs in nested position, the legs coordinating with the arms to simultaneously fold the same into overlying position on 20 the frame adjacent the back, in this way providing a novel folding chair construction with arm rests which is simply and quickly set up in position or folded compactly for 25 storage purposes.

Having thus described my invention and illustrated its use, what I claim as new and desire to secure by Letters Patent, is—

1. A folding chair comprising a frame including a back, a seat pivotally mounted on 30 said frame, arm rests mounted on said frame, pivotal mounting means for said arm rests, the pivotal connection for said arm rests being arranged to permit a lateral pivotal 35 movement of the arm rests within the confines of said frame, and operating means connected with said seat for folding said arm rests in the aforementioned position.

2. A folding chair including in combination a frame and back therefor, a seat pivotally mounted in said frame, arm rests disposed on said frame, mounting means for said arm rests to pivotally dispose the same laterally within the confines of said frame, legs 40 pivotally mounted on said frame connected 45 with said seat and means disposed from said legs connected with said arms to cooperatively fold said arms upon pivotal movement of said seat.

3. A folding chair comprising spaced up- 50 rights forming the frame, a seat arranged between said uprights, pivotally connected with said uprights, rear legs pivotally connected with said uprights, having engagement with the rear portion of said seat, 55 arm rests disposed from said uprights, means for mounting said arm rests in pivotal connection with said uprights, laterally into the plane of said frame and into 60 the confines thereof, means connecting said arm rests with portions of said rear legs to cooperatively move said arms by movement of said legs.

4. A folding chair comprising spaced up- 65 rights, a seat arranged therebetween, and pivotally connected with said uprights, rear

legs pivotally connected to said uprights and having slideable connection with said seat, arm rests each having lateral pivotal mounting on said uprights and connecting means between said arm rests and portions of said legs whereby relative movement of said legs and uprights will serve to coordinately swing said arm rests into folded position laterally with the folding movement of said legs and seat.

5. A folding chair comprising spaced uprights, a seat arranged between, pivotally connected with said uprights, the pivotal connection being at an intermediate point in the length of the seat, rear legs pivotally connected to said uprights, leg engaging means on said seat arranged to have sliding engagement with said legs, arm rests mounted on 80 said uprights, laterally pivotal mounting means for said arm rests, extensions on said legs and connecting means between said extensions and arm rests to cooperatively move said arm rests to the folded position within the confines of the frame with movement of 85 said rear legs to the folded position.

6. In a folding chair, a pair of side frame members spaced apart, including legs, a seat pivotally mounted between said members, arm rests each having a lateral and vertical 90 pivotal connection on said side members for movement inwardly and upwardly within the confines of the side members and outwardly in arm resting position, and cooperating connecting means between said seat and arm rests comprising a support for the seat 95 whereby the arm rests may be coordinately unfolded and folded with the unfolding and folding of the chair and the arms may be folded clear of the folded position of the seat.

7. A folding chair including a frame including spaced side members, a seat pivotally mounted on said side members, legs connected with said side members and seat for coordinate folding movement, arm rests each having a lateral pivotal connection mounted on 100 said side members, extensions on said legs formed with camming slots, engaging members on said arms to guide said arms to the folded and unfolded position by movement 105 of said seat.

8. A folding chair including a frame including spaced side members, a seat pivotally mounted on said side members, legs connected with said side members and seat for coordinate folding movement, arm rests including mounting means pivotally and tiltably, hingedly mounted on said side members, extensions on said legs formed with camming slots, engaging pin members on said arms to guide said arms to the folded and unfolded 110 position by movement of said seat and in the folded position clear of said seat.

9. A folding chair including a frame including spaced side members, a seat pivotally 115

- mounted between said side members, folding legs connected with said frame, arm rests free at one end and having the opposite end disposed on said frame, lateral hinged mountings for said arms for movement in relation to said side members, camming portions on said legs engaging complemental portions on said arm rests to fold and unfold said arms with the folding and unfolding of said legs.
- 10 10. A folding chair including a frame including spaced side members, a seat pivotally mounted between said side members, folding legs connected with said frame, arm rests free at one end and having the opposite end disposed on said frame, lateral hinged mountings for said arms for movement in relation to said side members, camming portions on said legs adjacent said arms, complemental pins on said arms, engaging said camming portions to fold and unfold said arms by folding movement of said legs.
- 15 11. A folding chair including a frame having spaced side members, a seat pivotally mounted therewith, folding legs connected to said frame, arm rests disposed on said frame, laterally hinged mounting for each of said arm rests, the hinges for said arm rests being formed to provide lateral movement of the arm rests in relation to said side members, a camming plate and complemental pin in cooperative engagement with each other, disposed on adjacent portions of each of said arm rests and legs whereby movement of said seat will fold and unfold said arm rests.
- 20 12. A folding chair including a frame including spaced side members, a seat pivotally mounted between said side members, folding legs connected with said frame, arm rests free at one end and having the opposite end disposed on said frame, tilttable laterally hinged mountings for said arms, extensions on said legs, camming plates on said extensions, complemental pins on said arms adjacent to said camming plates and lying transversely thereto whereby movement of said legs will fold and unfold said arm rests.
- 25 30 35 40 45

In witness whereof I have hereunto signed
my name this 21st day of November, 1928.

VINCENT RUIZ.
